MERCURY VAPOR RECTIFIER

Application filed January 8, 1923, Serial No. 611,530, and in Germany January 19, 1922.

The exhaustion of a mercury vapor rectifier necessitates generally the use of an air pump combination comprising a preliminary vacuum pump and a high vacuum pump. As 5 a rule the preliminary vacuum pump so used is a mechanically driven rotary air pump working under oil, while latterly, the high vacuum pumps employed have been of the type known as mercury-vapor air pumps in 10 which mercury is heated and the mercury vapor thus formed is cooled again, the air being carried along by the flowing mercury vapor and compressed into that part of the pump where the connection with the suction 15 pipe of the preliminary vacuum pump is situated.

The present invention has for its object to construct an improved mercury vapor rectifier wherein a separate high vacuum pump 20 is dispensed with and the flow of the mercury vapor of the rectifier is itself utilized for producing a pumping action, without interfering with the operation of the rectifier proper.

25 The mere location of a complete pump in the interior of the rectifier affords of itself no advantage because, owing to the difficulties of systematic cooling, neither the enclosed pump nor the rectifier would work in 30 a reliable manner.

According to this invention however the improved rectifier is constructed without substantial complication in such a manner that the parts which it must necessarily comprise 35 are made to serve at the same time for rectification of the electric current as well as for the exhaustion of the air from the rectifier vessel. This result is achieved by providing a guide tube for the mercury vapor rising 40 from the cathode.

In a mercury vapor rectifier having a cooling top situated above the cathode, and having anodes arranged laterally of the latter, the rising mercury vapor is led by a 45 guide tube into said cooling top of the recti-

fier for the purpose on the one hand of keeping said mercury vapor away from the anode spaces and of imparting to it a predominantly upwardly directed velocity in such a manner that a compression or condensation of the air takes place at that point of the cooling top where the suction pipe of the preliminary vacuum pump is connected. 50

The operation of the improved apparatus as a rectifier proper is attended thereby by 55 the great advantage that the anode spaces are almost free from mercury vapor so that the danger of back-ignition is very considerably diminished, while for its operation as a pump there is no necessity in general to 60 vary the direction of flow of the mercury vapor or to alter the design of the cooling device which is necessarily provided.

The connection of the preliminary vacuum pump is effected at the highest point of the 65 cooling top where the compression or condensation of the air takes place in consequence of the pumping action of the apparatus. It is necessary that the guide tube shall project into the cooling top in order that the mingling of the air with the mercury vapor shall take place only at a point where the mercury vapor begins to pass over in the 70 form of mist, which in the present case takes place shortly after the vapor has entered 75 the externally cooled top.

This invention will now be described more fully with reference to the constructional example illustrated in the accompanying drawing which is a vertical section of an improved rectifier according to this invention. 80

As shown:

G is a vessel of the mercury vapor rectifier.

D is the dome-shaped cooling top.

W is the water cooling jacket with inlet 85 and outlet z.

A₁, A₂ are the anodes of the rectifier.

R is a cylindrical tube for guiding the mercury vapor.

y is the suction pipe leading to the preliminary vacuum pump.

Q is the particular space in the cooling top D where the air flowing through the annular space N mingles with the rising mercury vapor.

O is the particular space in the cooling top D where the air carried along or over by the mercury vapor is liberated and in which therefore a compression or condensation of the air takes place.

The arrowed line L indicates the course of the electric arc between the anode and the cathode. The mercury vapor passing off from the cathode, is guided upwardly by the tube R with high velocity into the cooling dome D. At the point where said mercury leaves the guide tube R it has come between the water-cooled walls of the cooling dome, and is converted into mist. This mist has a tendency to mingle with the air already contained in the rectifier and air flowing in through the annular space N, and it carries the air thus imprisoned by it along with it in the direction of the flow of the mercury mist.

As the mercury mist becomes gradually completely condensed, the air that has been carried along by it becomes free approximately at the point O whence it is sucked away through the suction pipe *y* of the preliminary vacuum pump. The condensed mercury vapor falls down again in drops through the guide tube R, or outside the latter back into the dish of the cathode.

In this manner a high vacuum is gradually produced in the rectifier without requiring a separate high vacuum pump.

For starting the rectifier for the first time the use of a high vacuum pump may be required, but in such a case it is sufficient to provide for the use of the entire installation a single such pump which serves only for the first "forming" of the several rectifiers, after which it is thrown out of operation by means of a by-pass.

What I claim is:

1. In a mercury vapor rectifier, a mercury cathode, a cooling top provided with a suction outlet at approximately its highest point located above said cathode, anodes located laterally of said top, and a tubular member located between said anodes and above said cathode and below said cooling top, said member being of smaller cross-sectional passage area than said top and being disposed with its upper end projecting into the same to guide mercury vapor rising from said cathode into said top and to impart such velocity and direction to such rising vapor as to cause air carried upwardly thereby to be carried in proximity to said outlet for exhaustion therethrough.

2. In a metal vapor rectifier, a casing, a vapor-condensing chamber therefor pro-

vided with an air outlet, a cooling element disposed about said chamber and having an end extending interiorly of said casing, a cathode, a vapor-guiding element associated with said cathode and having an end arranged in proximity to said end of said cooling element and providing therewith an air-ejecting nozzle for effecting evacuation of air from said casing by way of said outlet.

In testimony whereof I have signed my name to this specification.

DR. HEINRICH MEYER-DELIUS.
